OF ST. LOUIS, MISSOURI, A CORPORATION OF MISSOURI.

DAY BED.

Application filed July 11, 1921. Serial No. 483,773.

To all whom it may concern:

Be it known that I, WILLIAM E. FRANK, a citizen of the United States, residing at St. Louis, Missouri, have invented a certain 5 new and useful Improvement in Day Beds, of which the following is a full, clear, and exact description, such as will enable others skilled in the art to which it appertains to make and use the same.

10 This invention relates to day beds of the type in which the extensible section is slid- 15 ingly mounted with relation to the stationary section and is arranged underneath said stationary section when it is not in use.

15 One object of my invention is to provide a practicable day bed of simple design and neat appearance that can be easily converted from a couch or single bed into a double bed and vice versa, and which is so con- 20 structed that the frame of the extensible section will be perfectly rigid when said extensible section is arranged in operative position to form a double bed.

25 Another object is to provide a day bed of the general type referred to in which the frames of the two co-operating sections are spaced far enough apart when the extensible section is in its inoperative position to provide adequate space between them for a 30 mattress in the event the mattress supporting portions of said sections are composed of woven wire fabric or a linked structure.

35 And still another object is to provide a day bed in which both the stationary section and the extensible section are provided with coiled or spiral springs for supporting the mattress, thereby producing a day bed that is as comfortable to lie upon as an ordinary double bed equipped with box springs 40 and which is as comfortable to sit upon when the extensible section is not in use as an ordinary upholstered couch or davenport. Other objects and desirable features 45 of my invention will be hereinafter pointed out.

Figure 1 of the drawings is a perspective view of a day bed constructed in accordance with my invention, showing the extensible section arranged in its inoperative position.

50 Figure 2 is a perspective view of a portion of the mechanism that is used to raise

and lower the mattress supporting portion of the extensible section.

Figure 3 is a perspective view of my im- 55 proved day bed, showing the extensible sec- 50 tion arranged in its operative position.

Figure 4 is a top plan view of portions 60 of the spring frames of the two sections, showing one of the devices that is used to draw said frames together when the spring frame of the extensible section is raised; and

Figure 5 is a detail sectional view of the 65 parts shown in Figure 4, taken on the line 5—5 of Figure 3.

I have herein illustrated my invention embodied in a day bed composed of a stationary section and an extensible section having mattress supporting portions formed by frames equipped with coiled or spiral 70 springs, but I wish it to be understood that it is immaterial, so far as my broad idea is concerned, whether said frames are equipped with coiled or spiral springs or with a woven wire fabric or linked structure 75 for supporting the mattress.

Referring to the drawings which illustrate the preferred form of my invention, A designates a frame that is combined with a foot piece B and a head piece C of any preferred 80 construction to form the stationary section of a day bed and D designates a frame that is combined with a shiftable supporting structure E, hereinafter referred to as a base frame, to form the extensible section of 85 said day bed. The frame A of the stationary section may be of any preferred construction and it can be equipped with any suitable means that will serve as a support for a mattress. In the form of my invention 90 herein illustrated the frame A of the stationary section, which I will refer to as a spring frame, is of oblong shape in general outline and is provided with transversely-disposed cross pieces 1 that support coiled 95 or spiral springs 2, as shown in Figure 1, said frame being composed of two longitudinally-disposed side members 3, two transversely-disposed end members 4 and four vertically-disposed corner members 5 formed 100 preferably from angle iron and joined together in such a way as to form a rigid frame

which can either be permanently connected to or detachably connected to the foot piece and head piece B and C, respectively, of the stationary section of the bed. The base frame E of the extensible section of the bed consists of a rigid oblong-shaped frame, constructed preferably from pieces of angle iron and combined with the stationary section of the bed in such a manner that it can be shifted laterally into a position at one side of the stationary section, as shown in Figure 3, or shifted in the opposite direction into the vertical plane of said stationary section, as shown in Figure 1. One convenient way of constructing the bed is to provide the front side of the base frame E with legs 6 equipped with rollers or casters 7 and provide the rear side of said base frame E with upwardly-projecting arms or uprights 8 provided at their upper ends with hooks 9 (see Figure 1) that lap over and slide upon horizontally-disposed rails 10 secured to the corner members 5 of the spring frame of the stationary section of the bed. The spring frame D of the extensible section is similar to the spring frame of the stationary section, in that it consists of an oblong-shaped frame provided with transversely-disposed cross pieces 1^a that support coiled or spiral springs 2^a, but said spring frame D is combined with the base frame E of the extensible section in such a manner that it can be raised and lowered with relation to said base frame. When the extensible section is in its inoperative position, as shown in Figure 1, the spring frame D lies close enough to said base frame to provide a considerable space between the spring frames of the stationary section and the extensible section of the bed, thereby making it practicable to use coiled or spiral springs on the extensible section to form a support for the mattress. In cases where the mattress supporting portion is formed by a woven wire fabric or a linked structure, there is ample space between the frames A and D of the two sections to store away the mattress during the day when the extensible section of the bed is not in use. When it is desired to convert the bed into a double bed the base frame E of the extensible section is pulled forwardly and the spring frame D of said extensible section is moved upwardly into horizontal alignment with the spring frame A of the stationary section, as shown in Figure 3.

Various means can be used for raising and lowering the spring frame of the extensible section and for rigidly supporting said spring frame in its elevated position, but I prefer to connect the spring frame D of the extensible section to the base frame E by four pairs of toggle links, each of which comprises a link 11 pivotally connected at 12 to the base frame E, a link 13 pivotally connected at 14 to the spring frame D and pivo-

tally connected at 15 to the upper end of the link 11, and a rigid curved arm or extension 13^a on the link 13 formed in such a manner that when the toggle is straightened to raise the spring frame D, the lower end of said arm 13^a will bear against the base frame E, and thus form a rigid one-piece strut between the spring frame D and the base frame E. In other words, each toggle of the four toggles that are used to raise and lower the spring frame D comprises a one-piece strut (formed by the link 13 and the extension 13^a thereof) whose upper end is pivotally connected to the spring frame D and whose lower end is brought into snug engagement with the base frame E when the toggles straighten. It will thus be seen that while the link 11 of each toggle co-operates with the link 13 to raise the spring frame D, the weight or load imposed upon the spring frame D when said frame is elevated is transmitted directly to the base frame E, not by the links 11, but on the contrary, by the rigid extensions 13^a of the links 13. When the toggles are broken or collapsed the free ends of the rigid extensions 13^a of the links 13 swing upwardly into the position shown in Figure 1, the spring frame D being provided with stops or laterally-projecting pins 16 against which the extensions 13^a of the links 13 strike when said spring frame is depressed.

Various means can be used for actuating the toggles that raise and lower the spring frame D of the extensible section of the bed, but one means that I have found to be very efficient, reliable and easy to operate consists of an oscillating actuating member F rockably mounted on vertically-disposed brackets 17 arranged at approximately the center of the base frame E and connected by pairs of links 18 and 19 with the pairs of toggles arranged at the opposite ends of the bed, said actuating member F preferably consisting of two inverted T-shaped portions pivotally connected at 20 to the brackets 17 and having their upwardly-projecting, vertically-disposed parts joined together by a cross piece 21, as shown in Figure 2, the links 18 being connected to one end of the horizontally-disposed parts of said inverted T-shaped portions and the links 19 being pivotally connected to the other end of said horizontally-disposed parts. The horizontally-disposed part of one of the inverted T-shaped portions of the actuating member F is provided with an integral extension or handle 22 by means of which said member F is operated. In practice I prefer to construct the member F in such a way that the cross piece 21 of same bears against the underside of the spring frame D of the extensible section of the bed when said member is turned in a direction to raise said frame so that the intermediate portion of said

frame will be supported by the member F, thus insuring an absolute rigid support for the spring frame D composed of four pairs of toggle links that support the end portions 5 of said frame and a transversely-disposed supporting element located at the center of said spring frame. The links 18 and 19 are provided with curved portions and are pivotally connected to the actuating member F 10 in such a manner that the pivotal connections between said parts are so arranged with relation to the axis of rotation of the member F that the links 18 and 19 will securely hold the toggle links straight or in 15 their extended condition when the handle 22 is swung to the left into the position shown in Figure 3.

In order to prevent the spring frame D of the extensible section from moving laterally with relation to the spring frame A of the stationary section of the bed, one of the longitudinal members of the frame D is provided with devices 23 of such form and arrangement that they will engage one of the 25 longitudinal members 3 of the spring frame A when the spring frame D of the extensible section is elevated, and thus prevent the spring frame D from swaying or moving laterally away from the spring frame A, the 30 devices 23 having upwardly inclined portions, as shown in Figure 5, that move into engagement with the adjacent longitudinal member of the spring frame A when the spring frame D is elevated and thus tend to draw said frames together. In other words, 35 I do not rely upon the supporting toggles for the spring frame D to hold said frame rigidly in its operative position, but I provide separate devices on the frame D that 40 move into engagement with the frame A in such a way as to draw the frame D towards the frame A and hold said frame D from swaying or from moving outwardly away from the frame A of the stationary section 45 of the bed. As this drawing together of the frames D and A is effected automatically, and as the raising and lowering of the spring frame D of the extensible section is effected by simply swinging a hand lever in one direction or the other, it is a very simple matter to convert the bed into a double bed or 50 into a single bed or couch.

A day bed of the construction above described is inexpensive to manufacture; it is 55 light in weight; it presents a neat appearance and when the extensible section is in operative position, it forms a double bed that is as comfortable to lie upon as an ordinary stationary double bed equipped with 60 box springs, due, of course, to the fact that the spring frames of the two co-operating sections are provided with coiled or spiral springs that support the mattress. When the extensible section is in its inoperative 65 position the bed is as comfortable to sit upon

as an ordinary couch or davenport, owing to the fact that the seat portion of the structure is equipped with coiled or spiral springs similar to those used in upholstered couches and davenports. 70

Having thus described my invention, what I claim as new and desire to secure by Letters Patent is:

1. A day bed, comprising a stationary section provided with a mattress supporting means, an extensible section comprising a base frame, and a mattress supporting means, and a collapsible supporting structure for the mattress supporting means of the extensible section comprising means for raising and lowering said mattress supporting means and rigid struts combined with said raising and lowering means and adapted to bear against said base frame when the mattress supporting means carried by said structure is in its elevated position. 75

2. A day bed, comprising a stationary section provided with a spring frame, an extensible section provided with a spring frame, a collapsible supporting structure for raising and lowering the spring frame of the extensible section, rigid struts for said extensible section spring frame combined with said collapsible supporting structure in such a way that said struts become operative automatically when said spring frame reaches its elevated position, and means for preventing the spring frame of the extensible section from swaying or moving laterally away from the spring frame of the stationary section when said extensible section is in use. 90

3. A day bed provided with an extensible section, comprising a base frame, a spring frame, toggles connected to said frames for raising and lowering the spring frame, and rigid elements combined with said toggles in such a way as to form rigid supporting struts for the spring frame when said frame is in its elevated position. 105

4. A day bed provided with an extensible section, comprising a base frame, a spring frame, pairs of toggle links that join said frames together, and a rigid arm or extension on one link of each of said pairs that moves into engagement with one of said frames when the spring frame is elevated and thus forms a rigid supporting strut for the spring frame. 110

5. A day bed provided with an extensible section, comprising a base frame, a spring frame, toggle links for raising and lowering said spring frame permanently connected to said frames by pivots, an actuating member for said toggle links provided with a portion that is adapted to serve as a support for the intermediate portion of the spring frame when said frame is in its elevated position, and rigid links pivotally connected to said actuating member and to said toggle links. 120

6. A day bed provided with an extensible 125

section, comprising a base frame, a spring frame, toggles for raising and lowering said spring frame, an actuating member, and links that join said actuating member to said toggles, said toggles having portions that form rigid struts between said frames when said spring frame is in its raised position.

7. A day bed, comprising a stationary section having a spring frame equipped with coiled or spiral springs, an extensible section comprising a base frame slidingly mounted on said stationary section, a spring frame

joined by toggles to said base frame and equipped with coiled or spiral springs, means for actuating said toggles so as to 15 raise and lower the spring frame of the extensible section, co-operating devices on said spring frames for preventing said frames from separating or pulling apart when the extensible section is in use, and portions on 20 said toggles that form rigid struts for the spring frame of the extensible section when said frame is in its elevated position.

WILLIAM E. FRANK.
